(57) **CLAIM**

The ornamental design for a MOUNTING PLATE as shown and described.

DESCRIPTION

FIG. 1 is a top perspective view of a MOUNTING PLATE showing our new design;

FIG. 2 is a bottom perspective view of the MOUNTING PLATE of FIG. 1.

FIG. 3 is a top view of the MOUNTING PLATE of FIG. 1.

FIG. 4 is a bottom view of the MOUNTING PLATE of FIG. 1.

FIG. 5 is a right side view of the MOUNTING PLATE of FIG. 1.

FIG. 6 is a left side view of the MOUNTING PLATE of FIG. 1.

FIG. 7 is a front view of the MOUNTING PLATE of FIG. 1.

FIG. 8 is a rear view of the MOUNTING PLATE of FIG. 1. The broken lines depict portions of the MOUNTING PLATE that form no part of the claimed design.
